(57) **CLAIM**

I claim the ornamental design for a figurine articulated hand, as shown and described.

DESCRIPTION

FIG. 1 is a perspective view of a figurine articulated hand, showing my new design;

FIG. 2 is a top perspective view thereof, illustrated with fingers thereof in a straight orientation;

FIG. 3 is a bottom perspective view of FIG. 2;

FIG. 4 is a front elevational view of FIG. 2;

FIG. 5 is a rear elevational view of FIG. 2;

FIG. 6 is a right-side elevational view of FIG. 2;

FIG. 7 is a left-side elevational view of FIG. 2;

FIG. 8 is a top plan view of FIG. 2; and,

FIG. 9 is a bottom plan view of FIG. 2.

The broken lines showing a figurine in FIG. 1 are environmental and form no part of the claimed design.
